CLAIM

The ornamental design for a floating desk, as shown and described.

DESCRIPTION

FIG. 1 is a perspective view of the floating desk showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings are included for the purpose of illustrating portions of the floating desk that form no part of the claimed design.

1 Claim, 7 Drawing Sheets
